EMBROIDERED FABRIC

Joseph Schifter, New York, N. Y.

Application January 26, 1933, Serial No. 653,580

3 Claims. (Cl. 112—266)

This invention relates to improvements in embroidered fabrics.

One of the objects of this invention is to modify the conventional double-thread diagonally-disposed cross-stitching of an embroidered fabric so as to produce a fabric having new designs of cross-stitching and particularly to provide a design including a six-sided hexagonal figure which will comprise exposed threads or 5 stitchings composed of cross-threads or cross-strokes with one or a plurality of exposed longitudinal threads or stitches arranged between the cross-strokes to provide hexagonal figures of varying longitudinal extent, instead of the usual 10 15 four-sided parallelograms comprising the conventional diagonally-disposed cross-stitching.

Still another object of my invention is to produce a double-thread cross-stitched embroidered fabric having units of embroidery stitching, 20 each comprising diagonally-disposed cross-strokes in continuous series or connection with one or a plurality of longitudinal stitches. By thus utilizing the cross-strokes in continuous 25 series or connection with one or a plurality of longitudinal stitches, a hexagon of a given width may be produced and by employing the cross-strokes in connection with a plurality of successive longitudinal stitches I am enabled to 30 modify the appearance of the aforesaid hexagonal or six-sided figure.

Still another object of my invention is to provide an embroidered fabric having an embroidered stitching the appearance of which may be noticeably changed or modified by simply 35 changing the height or width of the stitches.

Still another object of my invention is to provide embroidery stitching of the type hereinabove specified that may be produced by suitable machinery and preferably by the modification of 40 a conventional universal-feed embroidery machine.

With these and other objects in view, the invention comprises in one of its adaptations, the 45 species or preferred form illustrated in the accompanying drawing in which:—

Fig. 1 is a plan view of a piece of embroidered fabric having a composite stitch embodying my invention;

Fig. 2 is a similar view of a piece of embroidered fabric having a modified form of stitch embodying my invention;

Figs. 3 and 4 are views similar to Figs. 1 and 2 showing my designs applied over the tapes;

Figs. 5 to 8 are views showing stitch designs

similar to Figs. 1 and 2 respectively, but have the parallel rows of stitching narrowed;

Fig. 9 is an enlarged view in plan showing composite design-forming threads of the design illustrated in Figs. 1, 3, 5 and 7 and showing the loops or chains produced on the opposite side of the fabric in dotted lines;

Fig. 10 is a bottom view of an embroidered fabric of the type shown in Fig. 9.

Referring now to this drawing my invention 10 enables the production of embroidered fabrics having new designs of cross-stitching and particularly enables the production of an embroidered fabric having a design including a six-sided hexagonal figure such as shown in 15 Figs. 1 to 9 and which will comprise exposed threads or stitches composed of cross-threads or cross-strokes 1 and 2 crossing each other intermediate their ends, each being connected with one or a plurality of exposed longitudinal threads 20 or stitches 1^a and 2^a arranged between the cross-threads or stitches to provide hexagonal figures of varying longitudinal extent instead of providing fabrics having the usual four-sided parallelogram obtained by the conventional 25 diagonally disposed cross-stitching or cross-threading.

It will be understood that conventional fabrics were heretofore provided with stitchings having two threads provided with diagonal portions 30 crossing each other intermediate their ends to provide between the two rows of chain stitchings a four-sided parallelogram or figure and that by the use of my invention, I modify the stitching design required and change the direction of 35 some of the stitches to produce a fabric having the hexagonal or six-sided design as hereinabove specified.

In the preferred form of my invention illustrated, I produce a fabric provided with what I 40 shall term a double unit of embroidery stitching comprising two like units and each of these units will be formed by a single thread and will comprise one or more diagonally disposed exposed cross-threads or stitches in continuous 45 series or connection with one or a plurality of exposed longitudinal threads or stitches, the said cross threads in a double unit crossing each other intermediate their ends, and the longitudinal stitches of a double unit being disposed 50 parallel to each other, and by the use of my invention, I am enabled to produce a fabric having a double stitch design in which the stretch of the exposed threads or stitches will vary from 55 one another and particularly in which the cross-

threads vary in stretch or extent from the longitudinal threads whereby I am enabled to change or modify the appearance of the embroidered stitching by varying the widths of the double stitching or varying the distance between the 5 parallel rows thereof.

In accordance with my invention, I also insert beneath the exposed threads or stitches a tape 48, and in Figs. 3 and 4, I have shown tapes 48 10 inserted beneath the exposed threads of the thread designs.

Having described my invention, I claim:—

- 15 1. An embroidered fabric comprising, in combination, a piece of fabric having embroidered therein composite stitching composed of a pair of threads, said stitching embodying successively interconnected stitches presenting on one face of the fabric stitches disposed in spaced parallel rows and cross-strokes disposed transversely of said spaced parallel rows of longitudinal stitches and intersecting each other intermediate their ends, said stitches being interconnected with each other on the reverse side of the fabric.
- 20 2. An embroidered fabric comprising, in combination, a piece of fabric having embroidered therein composite stitching composed of a pair of threads, said stitching embodying diagonally-

disposed cross-strokes and longitudinal stitches on one face of the fabric and interconnected on the reverse side of the fabric, the cross-strokes intersecting each other intermediate their ends and said cross and longitudinal stitches being disposed in relation to each other at an angle greater than a right angle, the said stitching on one face of the fabric being employed to produce hexagonal figures in said composite stitching. 5

3. An embroidered fabric comprising, in combination, a piece of fabric having embroidered therein composite stitching composed of a pair of threads, each of said threads having a plurality of cross-strokes disposed at an acute angle in relation to the corresponding stitches of the 15 other of said threads, said cross-strokes being connected with a plurality of longitudinal stitches, the cross-strokes having diagonal portions crossing each other intermediate their ends, and said diagonal portions of said cross-strokes each being disposed in relation to a longitudinal stitch at an angle greater than a right angle, whereby said stitching may be employed to produce in said embroidered fabric hexagonal figures, and one side of each of said 20 hexagonal figures will comprise a plurality of 25 stitches.

JOSEPH SCHIFTER.
